UNITED STATES PATENT OFFICE.

WILLIAM S. HAMM, OF HUBBARD WOODS, AND THOMAS A. LEGGE, OF CHICAGO, ILLINOIS, ASSIGNEES TO THE ADAMS & WESTLAKE COMPANY, A CORPORATION OF ILLINOIS.

CLOSET-SEAT.

1,024,568.

Specification of Letters Patent.

Patented Apr. 30, 1912.

Application filed October 9, 1911. Serial No. 653,634.

To all whom it may concern:

Be it known that we, WILLIAM S. HAMM and THOMAS A. LEGGE, citizens of the United States, and residents of Hubbard Woods and Chicago, Illinois, respectively, have jointly invented certain new and useful Improvements in Closet-Seats, of which the following is a specification, and which are illustrated in the accompanying drawings, forming a part thereof.

The invention relates to seats for toilet closets, and more particularly to those which are hinged to swing upwardly and are associated with a hinged cover.

15 The object of the invention is to provide a hinge connection for the seat and cover of such closets, whereby the seat is required to be raised with the cover before the seat and cover may be positioned, respectively, in the lowered and raised positions.

The invention is exemplified in the structure to be hereinafter described, and which is illustrated in the accompanying drawings, wherein—

25 Figure 1 is a perspective view illustrating a closet seat and cover of a form provided by the invention; Fig. 2 is a detail plan view of the same, some of the parts being broken away and others being shown in cross-section; and Figs. 3 and 4 are sectional views taken on the line 3—3 of Fig. 2, Fig. 4 showing the parts in a different position.

The usual supporting rail to which the seat and cover are hinged is shown in the drawings at 10. The seat is designated 11, and the cover 12.

In carrying out the invention a hinge of improved construction is provided for uniting the seat and cover, and for hingedly securing them to the supporting rail 10. Preferably two such hinges are employed, each of these being generally designated by the numerals 13 in Fig. 1 of the drawings. As shown, each of the hinges 13 comprises three leaves or parts, designated 14, 15 and 16, respectively. Preferably all of these parts are partially connected by a common pivot or hinge pin, shown at 17.

50 The part 14 of the hinge is intended to be permanently attached to the supporting rail 10. To this end it is of the usual angular L shape, comprising horizontal and vertical arms designated 18 and 19, respectively, each of which is apertured to receive attach-

60 The parts 15 and 16 of the hinge are intended for attachment to the cover and seat, respectively. As shown, each comprises a pair of parallel arms, as 21, 22, and 23, 24, the arms of each pair being spaced apart to receive the inner edge of the seat or cover between them. One of the arms of each pair, as 21 and 23, is apertured to receive attaching screws, as 25, 26.

65 Provision is made for releasably connecting the parts 15, 16, of each of the hinges 13, whereby these parts are required to swing together, except when moved to an upright position corresponding to the open position of the seat and cover illustrated in Fig. 70 70. To this end a spring latch, as 27, is mounted in one of the parts, as 15, for engaging the other part, as 16. As shown, the spring latch 27 comprises a hook arm 28, which is pivotally mounted upon an instantiating lug 29 formed upon the lower one of the two parallel arms 21, 22, of the hinge part 15. This hook arm extends downwardly through an aperture 30 in the arm 22 of the hinge part 15, and releasably engages 80 the margin of an aperture 31 provided in the adjacent arm, as 23, of the hinge part 16. Preferably the seat and cover members 11, 12, are recessed, as indicated at 32, 33, to provide for the mounting of the hook arm 28 within the hinge part 15 and for the engagement of its protruding end with the hinge part 16.

75 To provide means for controlling the hook arm 28, it is preferably provided with a 90 rearwardly extending shank 34. This shank is shown as protruding through an aperture 35 in the rear or inner end portion of the hinge part 13. A leaf spring 36 bears upon the shank 34 of the hook arm 28 to 95 normally hold it in position for engaging the hinge part 16. As shown, this leaf spring plays within the recess 33 formed in the cover part 12 adjacent its inner edge, and is permanently secured to the under 100 side of the upper arm 21 of the hinge part 15, as by means of a headed stud 37.

105 Provision is made for causing the release of the hook arm 28 from the hinge part 16 when the seat and cover have been fully raised to permit the seat to be lowered independently of the cover, as indicated by dotted lines in Fig. 4. To this end the protruding end of the shank 34 of the hook arm has a cam engagement with the hinge part 110

14 when the cover member 12 is fully raised. As shown, the horizontal arm 18 of the hinge part 14 is provided with an aperture 38, and the inner edge 39 of this aperture is rounded to provide a cam shoulder for engaging the end of the shank 34. Preferably the supporting rail 10 is recessed, as indicated at 40, below the aperture 38, to permit the end of the shank 34 to protrude through the aperture.

In the arrangement provided by the invention the seat 11 and cover 12 swing upon a common pivot 17. When the cover 12 is closed the hook arms 28 of the two hinges 13 serve to connect the seat and cover, whereby on raising the cover the seat is necessarily raised with it. The engagement of the protruding ends of the shanks 34 of the hook arms 28 with the cam shoulders 39 causes a disengagement of the seat and cover members when they have been completely raised, to permit the seat to be lowered independently of the cover. When the seat and cover are brought together in the lowered position, or in any intermediate position, the hook arms 28 serve to connect them

whereby neither can be swung independently until both have been fully raised.

We claim as our invention—

1. In a closet seat, in combination, a support, a three-part hinge having one of its members fixed to the support, a spring latch pivoted on the intermediate member and engageable with the third member, the latch having a stem engageable with a trip pocket in the first-named hinge member, a seat attached to the third-named hinge member, and a cover attached to the intermediate hinge member.

2. In combination, a support, a three-part hinge having one of its members fixed to the support, and a spring latch pivoted on the intermediate member and engageable with the third member, the latch having a stem engageable with a trip on the first-named hinge member.

WILLIAM S. HAMM.
THOMAS A. LEGGE.
